ware

Application December 7, 1950, Serial No. 13,326

Term of patent 14 years

(Cl. D58—26)

To all whom it may concern:

Be it known that I, Jean Despres, a citizen of the United States, residing at New York, in the county of New York and State of New York, have invented a new, original, and ornamental Design for a Combined Perfume Bottle and Holder Therefor or Similar Article, of which the following is a specification, reference being had to the accompanying drawing, forming part thereof.

In the drawing:

Fig. 1 is a front elevational view of a combined perfume bottle and holder therefor or similar article showing my new design;

Fig. 2 is a side elevational view thereof;

Fig. 3 is a rear elevational view thereof;

Fig. 4 is a top plan view thereof.

I claim:

The ornamental design for a combined perfume bottle and holder therefor or similar article, substantially as shown.

JEAN DESPRES.
